UNITED STATES PATENT OFFICE.

ARTHUR L. KUHLMAN, OF BAY CITY, MICHIGAN.

ELECTRICAL RECEPTACLE.

Application filed February 8, 1923. Serial No. 617,676.

This invention relates to electrical receptacles and the like.

The prime object of the invention is to design an instantaneous connect and disconnect electrical receptacle, so that all forms of attachments or fittings, such as used on percolators, irons, lamps, and other electrical equipment will fit thereinto, and eliminate the necessity of the various forms and designs of fittings and attachments at present in general use.

Another object of the invention is to design a simple, durable and efficient receptacle composed of few parts, which are economical to manufacture and easy to assemble.

A further object is to provide a spring actuated automatic locking receptacle, which firmly grips and locks the plug or other fitting in place, but which will however allow it to spring free and prevent breakage in case of accident.

A still further object is to provide suitable releasing means so that the plug or other attachment can be inserted or released without rotation thereof.

A further object still is to provide a receptacle into which a plug or fitting can be plugged or removed by a straight in-push or pull, but which can also be rotated if desired to secure better adjustment with the center contact.

With the above and other objects in view, the present invention consists in the combination and arrangement of parts, herein-after more fully described, illustrated in the accompanying drawings, and particularly pointed out in the appended claims, it being understood that changes may be made in the form, size, proportion and minor details of construction without departing from the spirit or sacrificing any of the advantages of the invention.

In the drawings:—

Fig. 1 is a side view of my improved receptacle, the locking means being shown in two different positions, the dotted lines indicating the position of the locking members when a fitting is in position therein, and the full lines showing their position when the fitting is withdrawn.

Fig. 2 is an opposite side view thereof.

Fig. 3 is a top plan view of the receptacle proper.

Fig. 4 is an enlarged top plan view of one of the locking members.

Fig. 5 is a similar view of the other locking member.

Fig. 6 is an isometric view of one of the base plates.

Fig. 7 is an isometric view of one of the springs.

Fig. 8 is a side view of the receptacle as used in a wall or baseboard.

Fig. 9 is a front view thereof.

Fig. 10 shows an alternate form of construction.

Referring now particularly to the drawings in which I have shown the preferred embodiment of my invention, the numeral 1 indicates a porcelain base to which the receptacle proper is attached, spaced apart base plates 2 are secured to the face of this base by means of screws 3 and these screws form terminals for the wire connections 4 and 5 in the usual manner. Standards 6 are formed integral with these plates 2 and are provided with suitable openings 7 therein, adapted to receive the laterally extending lugs 8 which are formed on the legs 9^a of the locking members 9. These members 9 form the locking portion of the receptacle, and comprise a thin circular metal member formed with screw threaded surfaces which are adapted to mesh with and engage the threaded surface of the attachment, plug or fitting such as are found on the conventional incandescent light socket. It will also be noted that the ends of the threads are slightly flattened, this is to allow the fitting to be easily inserted and prevent its hanging and catching, and it will be found that the coarseness and roll of the thread facilitates the easy inserting of the attachment or fitting.

I wish to direct particular attention to the fact that both locking members are formed identically alike, excepting that the legs on the one member are offset as shown at 10, and are so spaced that when in assembled position, the legs on the opposite locking member engage therewith and are adapted to ride on this offset portion.

These locking members are held in position by means of flat spring members 11 which are adapted to be interposed between the standards 6, and these springs are formed with slots 12 in the ends thereof, which are adapted to straddle the standards 6, and in practice are rounded so that when the receptacle is assembled they will exert a continuous upward pressure against the legs

tending to force the threaded sections inwardly towards each other.

Laterally extending arms 13 are formed integral with the legs 9^a, the ends thereof being rounded over to receive and form a seat for the pin 14, which is formed integral with the shank of the push-button 15, and when the button is forced inwardly to position as shown in dotted lines in Fig. 1, the lugs 8 formed on the locking member will rock in the openings 7, the one pair of legs 9^a resting on the offset portion 10 of the other locking member will force both threaded sections outwardly to position as shown in dotted lines in the same figure, flexing the spring member 11 and releasing the plug attachment of fitting, a stop 10^a can be provided for limiting the inward movement of the members and when the button is released, the spring will again force the sections toward each other.

The contact 16 is of the conventional type, and it will be obvious that when the fitting is inserted in the receptacle, that it can also be rotated if desired and thereby force it further into the receptacle to secure a better contact if necessary.

In Figs. 8 and 9 I have shown the receptacle in the position it would occupy in a baseboard, in this construction the button 15 extends through an ordinary base plate 17 and engages the lug 13 which in this instance is secured to the upper end of the leg 9^a the action of the mechanism is however identically the same although a greater leverage is obtained.

In Fig. 10 I have shown an alternate form of construction, one of the locking members being stationary, the opposite locking member being pivoted to the plate 2 in the usual manner, the push-button 15 is pro-

vided with a longer shank and is pivotally connected to the legs at the point 18, this construction also provides sufficient movement to allow the fitting to be readily inserted and removed. 45

The action of these locking members is similar to the action of a pair of scissors excepting that the members are not pivotally connected together, the action of the one locking member being automatically communicated to the other. 50

From the foregoing description it will be obvious that I have perfected a very simple and economical instantaneous electrical connect and disconnect receptacle. 55

What I claim is:—

1. An electrical receptacle including a base, a pair of cooperating locking members pivotally secured thereto and comprising a pair of legs having a screw threaded arcuate metal section secured to the free end thereof, a shoulder formed on one pair of legs for engagement by the opposite locking member, resilient means interposed between the base and the locking members, and a push-button connected to one of the metal sections for forcing the locking members apart. 60

2. An electrical receptacle including a base, a pair of cooperating locking members pivotally secured thereto, one of said members having an offset leg portion on which the opposite member is adapted to ride, a spring interposed between the base and the locking members tending to normally force them towards each other, a stop for limiting the movement thereof, and a push-button connection for forcing said members apart. 75

In testimony whereof I affix my signature. 80

ARTHUR L. KUHLMAN.
